(57) **CLAIM**

The ornamental design of an identification tag, as shown and
described.

DESCRIPTION

FIG. 1 is a perspective view of an identification tag showing
my new design;

FIG. 2 is a front view thereof;

FIG. 3 is a back view thereof;

FIG. 4 is an edge view thereof; and,

FIG. 5 is a sectional view taken on the line 5—5 of FIG. 2.
The identification term shown in phantom in FIG. 1 is for
illustration only and forms no part of the design.
